UNITED STATES PATENT OFFICE.

JAMES CHISHOLM, OF FORT LISCUM, ALASKA TERRITORY.

CAN-OPENER.

SPECIFICATION forming part of Letters Patent No. 707,207, dated August 19, 1902.

Application filed January 20, 1902. Serial No. 90,526. (No model.)

To all whom it may concern:

Be it known that I, JAMES CHISHOLM, a citizen of the United States, at present stationed at Fort Liscum, in the Territory of Alaska, 5 have invented a new and useful Can-Opener, of which the following is a specification.

This invention is an improved construction of can-opener, the object being to provide an exceedingly cheap and simple device by 10 means of which the top of a can can be quickly and easily opened and all danger of cutting the hand during such operation entirely avoided.

Another object is to provide a can-opener 15 in which the cutting-blade can be quickly and easily adjusted to cut adjacent to or remote from the edge of the can, thereby cutting either a large or small opening, as preferred; and another object is to provide a 20 can-opener in which the cutting-blade can be adjusted with reference to the guiding portion of the cutter, so that the device can be used for opening all sizes of cans.

With these and various other objects in view 25 the invention consists of the novel features of construction and combination hereinafter fully described, and pointed out in the claims.

In the drawings forming a part of this specification, Figure 1 is a perspective view illustrating the application of my invention. Fig. 30 2 is a perspective view of the device as viewed from the under side. Fig. 3 is a detail bottom plan view, and Fig. 4 is a detail sectional view illustrating the blade-adjusting mechanism.

In carrying out my invention I employ a handle A, which is preferably formed integral with the body portion B, which is in the nature of a thick plate, the edge B' of which is 40 curved and provided with an undercut shoulder B², the edge B' and shoulder B² being constructed upon different curves and meeting at the point or end B³. The body is formed with an extension or projection C at 45 the side opposite the point or end B³, said projection or extension having an oblique slot C' produced therein and in which works the shank D' of the cutting-blade D, said shank having a head D², which rests upon 50 the top of the extension, being wider than the slot. An adjusting-screw E passes transversely through the shank D' and is provided with a milled head E', by means of which the screw is turned for the purpose of adjusting 55 the blade, said screw being arranged longi-

tudinally within the oblique slot, the inner end being journaled at the end of said slot, and a collar E² is fastened upon the screw and adapted to bear against the opposite end of the slot for the purpose of holding the 60 screw in its proper longitudinal position, so that by turning the head E' in either direction the blade can be adjusted as desired. The undercut shoulder B² is produced upon a slight inclination, as clearly illustrated in 65 Fig. 4, in order to prevent slipping during the operation of the device.

In operation the edge of the can is placed against the undercut shoulder B² and the blade D forced down through the top of the 70 can, and by pushing upon the handle and forcing the body around the edge of the can the cutting-blade is caused to travel around, cutting the top in a circular line adjacent to the edge of the can. The undercut shoulder 75 B² is curved in such a manner that it will snugly fit nearly all cans now in common use, and by adjusting the blade in or out the device can be made suitable for operation upon 80 all sizes of cans.

Having thus fully described my invention, what I claim as new, and desire to secure by Letters Patent of the United States, is—

1. A can-opener having a body provided with a curved undercut shoulder, a slotted 85 extension or projection, the cutting-blade adjustably arranged in said slotted extension, and an operating-handle connected to the body, as set forth.

2. A can-opener comprising a body portion 90 having a curved undercut shoulder, an obliquely-slotted extension or projection, a cutting-blade having its shank arranged in said slotted extension, and means arranged within the slot and connected to the shank for the 95 purpose of adjusting the blade, as set forth.

3. A can-opener comprising a body portion having a curved edge and a curved undercut shoulder, the obliquely-slotted extension or projection, the cutting-blade having its 100 shank located in said slot, the adjusting-screw working in the slot and passing through the shank and the operating-handle integral with the body portion, substantially as set forth.

JAMES CHISHOLM.
